UNITED STATES PATENT OFFICE.

ALBERT TANGENBERG, OF GRAND RAPIDS, MICHIGAN, ASSIGNOR TO ELECTRIC REFRIGERATION CORPORATION, OF DETROIT, MICHIGAN, A CORPORATION OF MICHIGAN.

REFRIGERATOR-CABINET CONSTRUCTION.

Application filed January 5, 1927. Serial No. 159,142.

This invention relates to refrigerator cabinets, and more particularly to an improved shoe construction which forms the base for the refrigerator cabinet structure, this shoe 5 being especially adapted for use with cabinets constructed with veneered end panels.

With refrigerators in which frame elements are associated together and covered at their ends, moisture will collect which will 10 tend to warp or rot the frame elements and to rapidly deteriorate the joints.

An object of the invention is to overcome the above condition by providing a passage in the refrigerator structure to permit air to 15 absorb the moisture that collects interiorly of the refrigerator wall structure under normal conditions.

Another object of the invention is to provide a passage in the refrigerator wall structure for draining off moisture under abnormal moisture conditions and to permit air to penetrate interiorly of the refrigerator walls under normal moisture conditions so as to maintain the refrigerator walls in a 25 dry condition.

These and other objects will be more apparent as the description progresses, in which like characters designate like parts in the drawing which illustrates a preferred 30 embodiment of the invention.

In the drawing:

Fig. 1 is a fragmentary section perspective view through one of the lower corners of a refrigerator cabinet,

35 Fig. 2 is a perspective view of the shoe incorporated in the refrigerator cabinet structure.

The refrigerator cabinet shown in the accompanying drawing illustrates the construction of one of the higher grade cabinets. The invention is well illustrated in the fragmentary perspective view (Fig. 1) in which 10 designates the end panel, which is preferably formed of a central board 11 40 having glued on both faces a plurality of relatively thin wood veneer sheets 12. Glued and nailed along the lower edge of the end panel 10 and against the inside surface thereof is the shoe block 13, which provides a shoulder or support 14 for the case bottom 15 of the refrigerator cabinet. Nailed to the case bottom 15 is the bottom cleat 16, to which is nailed or otherwise secured the inner bottom 17 of the cabinet. Insulation ma-

55 terial 18, preferably corkboard, is assembled between the case bottom 15 and inner bottom 17, and the insulation 19, preferably corkboard, is located adjacent the inner face of the end panel 10. The refrigerator lining 20 is fitted into the refrigerator compartment 21 and is preferably constructed of sheet metal coated on the inside surface with porcelain or enamel. Secured beneath the lower edge of the end panel 10 and shoe block 13, is a shoe 22 which is of greater 60 width than the thickness of the combined end panel and shoe block so as to project laterally inwardly in order to provide sufficient bearing surface for carrying the castors which provide a rolling support for the 65 refrigerator cabinet.

70 When the refrigerator temperature is maintained at a lower point than that of the surrounding air, condensation of the water vapor contained in the air is caused 75 by entrance of the warmer exterior air into the refrigerator and by the passage of cool air from the interior of the refrigerator to the exterior surfaces. Unless the frame of the refrigerator box is absolutely air tight, 80 which is an unusual condition, water formed by condensation of the water vapor penetrates into the frame of the refrigerator and settles therein causing rotting, warping, 85 swelling, and other similar results detrimental to the life of the refrigerator. This condition is relieved and overcome by the present invention which comprises forming a refrigerator box so that moisture within the frame will be collected and evaporated 90 by external air.

95 In order to preserve the refrigerator, the moisture arising within the refrigerator wall structure under both normal and abnormal conditions must be absorbed or carried away. To accomplish this I propose to provide a passage in the refrigerator structure for carrying this moisture off quickly or to permit the air to penetrate into the interior of the refrigerator wall structure. I find that one of the most critical points is adjacent the lower joint between the end panel 10, the shoe block 13 and the shoe 22, the moisture tending to collect at this point. Refrigerator cabinets have been constructed in recent 100 years with wood veneered end panels, and it is found that this moisture will quickly 105 penetrate into these veneered panels and

loosen the joint between the veneered sheets 12 and the inner board 11, causing the veneer to buckle and break.

I preferably construct this passage by 5 providing a groove 23 in the upper surface of the shoe 22, which groove forms a trough extending the entire length of and adjacent the outer edge of the shoe. It will be noted that the shoe is provided with a retaining 10 flange 24 along the outside edge, and the veneered end panel 10 abuts the top surface of the shoe just inside this retaining flange 24, the trough 23 being preferably located directly beneath the lower edge of the 15 veneered end panel.

Under abnormal conditions the moisture drips down onto the shoe 22 and gradually creeps along the top surface of the shoe towards the end panel. It will drip into 20 the trough 23 which extends from the front to the back of the box. The moisture is permitted to drain off through the trough to a point exterior of the box, where it is evaporated.

25 Under normal conditions a little moisture will collect interiorly of the refrigerator wall, and under this condition the trough serves as an air passage which permits the air to penetrate into the refrigerator wall 30 and evaporate the moisture.

With the construction above described the refrigerator wall structure is maintained in a dry condition, the moisture being carried away either by evaporation or by being permitted to drain off. As a result the life of 35 the refrigerator is considerably increased and the breeding of germs is checked, resulting in a more sanitary refrigerator.

Various changes in construction may be 40 made without departing from the spirit of the invention as pointed out in the appended claims.

What I claim is:

1. A refrigerator cabinet constructed of a 45 plurality of members joined together, a shoe providing a base for said cabinet and secured to one of said members, and means for carrying away moisture which collects adjacent the joint between the above mentioned cabinet members.

2. A refrigerator cabinet constructed of a

plurality of frame members joined together, and a shoe providing a base for said cabinet beneath said frame members, said shoe having a trough in the upper surface leading 55 to an exterior point of the cabinet.

3. A refrigerator cabinet including a bottom wall, an end panel, a shoe block secured thereto adjacent its lower edge forming a support for the bottom wall of the cabinet, 60 and a shoe secured to the lower edge of said end panel and provided with a trough leading to an exterior point of the cabinet.

4. A refrigerator cabinet including a bottom wall, an end panel constructed of a plurality of layers of wood glued together, a shoe block secured against the inside face of said panel for supporting the bottom wall of the cabinet, and a shoe secured to said shoe block and end panel, said shoe being 70 provided with means for carrying away moisture that collects in the interior of the refrigerator wall structure.

5. A refrigerator cabinet including a bottom wall, an end panel constructed of a plurality of layers of wood glued together, a supporting shoe block secured beneath said bottom wall, and a shoe secured beneath said shoe block and said end panel, said shoe having its top surface provided with an 80 open trough which extends the entire length thereof.

6. A refrigerator cabinet including a bottom wall, an end panel constructed of a plurality of layers of wood glued together, a shoe 85 block secured to the under surface of said bottom wall and the inner surface of said end panel, and a shoe secured beneath said shoe block and said end panel, said shoe being provided with a trough in its upper 90 surface running from the front to the back of the cabinet and located adjacent the lower edge of the end panel for providing a passage in said refrigerator wall structure to permit air to absorb moisture collecting at 95 an interior point of said wall structure and to drain off excess amounts of moisture under abnormal moisture conditions.

In testimony whereof, I hereunto affix my signature.

ALBERT TANGENBERG.
